OF D 19,131

LEWIS HASLAM, OF RAVENSWOOD, NEAR BOLTON, COUNTY OF LANCASTER,
ENGLAND.

DESIGN FOR A TEXTILE FABRIC.

Design No. 19,131, dated June 4, 1889.

UNITED STATES PATENT OFFICE.

LEWIS HASLAM, OF RAVENSWOOD, NEAR BOLTON, COUNTY OF LANCASTER,
ENGLAND.

DESIGN FOR A TEXTILE FABRIC.

SPECIFICATION forming part of Design No. 19,131, dated June 4, 1889.

Application filed April 9, 1889. Serial No. 306,592. Term of patent 14 years.

To all whom it may concern:

Be it known that I, LEWIS HASLAM, a citizen of England, residing at Ravenswood, near Bolton, in the county of Lancaster, England, have 5 invented and produced a new and original Design for Textile Fabrics, of which the following is a specification.

The object of this design is to provide a 10 novel and ornamental net-work fabric, as hereinafter described and claimed, and shown by the accompanying photographs, of which—

Figure 1 is a plan view showing one side of the fabric, and Fig. 2 a similar view showing the opposite side of the same.

15 The letter A indicates zigzagged or serpentine threads and B indicates approximately straight threads, of a thickness greater than the zigzagged threads and transversely crossing the latter. The threads A have the appearance of being joined at one side only of 20 the fabric, as at the points 3, Fig. 2; and D indicates parallel rows of rectilinear spaces or cells presenting the appearance of running in diagonal or oblique directions. The spaces

or cells D appear open and unobstructed at 25 one side of the fabric, while at the opposite side of the latter the spaces or cells appear as crossed and partially closed by the threads B, so that the fabric presents at one side the appearance of an open net-work, as in Fig. 1, 30 and at the opposite side the appearance of a partially-closed net-work, as in Fig. 2.

What I claim is—

The design for a textile fabric having zigzagged threads A, rectilinear spaces or cells D, 35 and on one side the approximately-straight threads B, crossing the spaces or cells and zigzagged threads, substantially as shown and described.

In testimony whereof I have affixed my signature in presence of two witnesses.

LEWIS HASLAM.
